UNITED STATES PATENT OFFICE.

SECONDO GILETTI, OF SAN FRANCISCO, CALIFORNIA.

CONCRETE SHIP.

1,313,592.

Specification of Letters Patent.

Patented Aug. 19, 1919.

Application filed July 9, 1918. Serial No. 244,085.

To all whom it may concern:

Be it known that I, SECONDO GILETTI, a citizen of the United States, residing at the city and county of San Francisco and State of California, have invented new and useful Improvements in Concrete Ships, of which the following is a specification.

This invention relates to concrete ships and pertains especially to the larger types 10 of self-propelled vessels which are constructed entirely of reinforced concrete.

A concrete vessel of the type referred to must be able to carry a large tonnage in addition to machinery, fuel, stores, etc., and 15 the problem involved is therefore a structure wherein lightness must be combined with great strength and resistance to local and exterior strains due to the natural forces of the elements, heavy tonnage and strains, 20 together with vibration resulting from the propelling machinery.

With these features in view it is one of the objects of the present invention to build a commercial, practical, sea-going self-propelled vessel constructed entirely out of reinforced concrete that will not be affected detrimentally either by the vibrations and strains of the machinery or by the action of the waves. Another feature of the invention 25 comprehends a monolithic structure of reinforced concrete in which the hull, ribs, girders, beams and decks are molded integral, the several members constituting a connected arched structure both longitudinally and transversely which is so arranged 30 that strains due to compression, sheering or bending are all resisted and taken care of whether from exterior or internal sources.

The invention furthermore comprises a specific construction, to-wit: First, a reinforced concrete vessel having a double bottom and sides which are connected by vertical and horizontal girders or ribs, together with a double deck structure, said 40 double sides not to extend above the lower deck. Second, ribs or girders connecting the double bottom and sides extend from stem to stern and so arranged as to form longitudinal arches which resist or support 45 the major longitudinal bending or compression strains to which the vessel is subjected, either from unequal distribution of load or from wave action. Third, the structure includes an exterior and an internal hull which 50 are reinforced by transverse ribs and con-

nected by slabs which in themselves form intermediate lateral arches transversely of the ship. Fourth, the structure includes a pair of longitudinal arches formed one on each side of the hull which extend from 55 stem to stern, said arches assisting the longitudinal arches formed between the double hull and bottom to resist all longitudinal strains. Fifth, the structure also includes decks in which the slabs form arches transverse of the vessel.

Other features will hereinafter be more clearly described having reference to the accompanying drawings, in which—

Figure 1 is a plan view of the ship.

Fig. 2 is a central, vertical, longitudinal section.

Fig. 3 is a cross section.

Fig. 4 is a perspective view showing a portion of the interior construction.

Fig. 5 is a detail sectional view taken on the line 5—5 of Fig. 4.

Referring to the drawings in detail, A indicates in general the upper deck of the ship, 2 a lower deck, and 3 the bottom, which in this instance, consists of two sections, as shown at 4 and 5, to permit the formation of an inner and an outer hull, the sides of which are shown at 7 and 8. The double hull and bottom extend from stem to stern 55 and are only formed below the lower deck shown at 2. The sides of the hull are connected at their upper ends by the lower deck, as shown at 9. They are furthermore connected by a longitudinal rib or girder 60 extending from stem to stern and they are finally reinforced by a second girder 11 which is angularly disposed and also arranged to extend from stem to stern. The inner and outer sections of the bottom are 65 also connected by girders, as shown at 12. Any suitable number of these girders may be provided, and, as they also extend from stem to stern, it can readily be seen that the longitudinal strength of the vessel is practically taken care of.

The slabs forming the inner and outer sections of the bottom are arched, as shown at 14. This not only increases the transverse strength of the bottom section, but 70 it materially increases the longitudinal strength of the same, thus further assisting in strengthening the vessel longitudinally. The ship is otherwise strengthened crosswise by laterally extending beams or girders 75

14'. These girders pass through the double bottom and sides of the hull, as shown at 15 and 16, and thereby not only serve as a means for connecting the double hull and 5 bottom sections, but also as a means for dividing the space formed between the same into a great number of entirely separated water-tight compartments. The upper portion of each girder is extended under the 10 lower deck line, as shown at 17, to form a support for the same and their outer ends are knee-shaped, as shown at 18, to form a rigid connection between the sides of the hull and also a tie between the same.

15 The slabs forming the sides of the hull are reinforced and tied together not only by the main girders 14' already referred to, but also by smaller intermediate girders 19 which extend from wall to wall. The small 20 intermediate girders are three in number in this instance and will therefore divide each compartment formed between the main girders 14' into four intermediate compartments all separated and water-tight with 25 relation to each other. Each main slab between two girders is therefore divided into four small intermediate slabs, and, as these are curved or arcuated, as shown at 20 and 21, the strength is enormously increased.

30 The lower deck and also the upper deck are similarly reinforced and constructed, that is, intermediate deck beams 22 are formed between the main girders or beams 17 which divide each main deck slab into a 35 series of smaller slabs. These slabs are also curved or arcuated in construction, and, as they extend transversely of the vessel, it can readily be seen that the strength of the ship in general is further increased without resorting to a heavy deck construction. The lower deck is supported entirely by the main beam 17 and the knees 18, while the upper deck is almost entirely supported by main 40 and intermediate beams 24 and 25 and up- 45 right posts 26 carried by the lower beams 17. Each deck is, of course, provided with longitudinal girders 27 which extend from stem to stern to increase the longitudinal strength of the ship.

50 For the purpose of further increasing the longitudinal strength of the ship or to permit it to completely withstand longitudinal compression and bending strains, a pair of main arches 30 have been provided. There 55 is one arch formed in each side and each arch extends substantially from stem to stern, as shown in Fig. 2. These arches are built integral with the outer sides or hull of the ship and the thickness of the same is 60 shown at 31 (see Fig. 3).

The reinforcing steel employed throughout the ship may be embedded and arranged in any suitable manner, but preferably as here shown, that is, every rod employed

should be electrically welded or tied to 65 eliminate any danger of separation when the ship is subjected to unusual strains, the rods employed in the longitudinal arches 30 being also electrically welded or similarly secured to the rods forming the bottom section and also to the rods carried by the main cross girders 14'. All the steel employed in the vessel is, in this manner, tied and secured at every conceivable point and the 70 strength obtained proportionately increased. 75

Longitudinal strains are taken care of not only by the main arch beams 30, but also by the vertical and horizontal girders 10, 11 and 12 formed between the double bottom and hull. Transverse strains are, of course, taken 80 care of by the main girders 14 and the intermediate girders 19 and also by the construction of the deck employed.

By referring to the drawings it will be seen that the slabs forming the sides, bottom and decks are all arcuate in construction, the arcs in the slabs forming the bottom sections extending longitudinally from stem to stern, while the arcs in the slabs forming the sides of the hull run transversely of the ship. This is of great importance as the strength of the slabs will, in this manner, materially assist in reinforcing the strength of the ship as a whole 85 against the several strains to which it is subjected. The slab structure furthermore permits the structure as a whole to be materially lightened and the amount of reinforcing steel employed to be proportionately reduced. The water-tight compartments 90 formed between the sides and the bottom of the hull sections are preferably formed by placing sheet iron molds or tanks between the sections while the ship is being cast. They therefore become thoroughly embedded in the concrete as it sets and furthermore become a permanent part of the structure. The spaces may therefore be used to advantage for the purpose of carrying fuel 95 oil, water, or any other material desired, the metal lined spaces or chambers referred to being employed only between the bottom 100 sections.

From the foregoing it will be seen that I have succeeded in dispensing with a great 115 quantity of material, said quantity being at least reduced by the amount of material that is eliminated from each slab, both in the sides and the bottom of the hull, thereby saving many tons in weight without in any way 120 impairing the strength of the vessel. The greatest slab thickness employed at any place will probably not exceed four inches and will, in most instances, be reduced to approximately two and one-half inches. A 125 hull having a thickness such as described should therefore have a great flexibility, in fact, almost equal to that of a ship con-

structed of steel plates. A reinforced concrete ship constructed as shown may therefore yield sufficiently to distribute all strains and will therefore not readily rack or 5 crumble from vibrations or other strains.

In considering the strength of the ship longitudinally account must be taken only of such material as actually contributes to the strength for an appreciable length in 10 the vicinity of the section. I secure this strength by employing the two main arches 30 described and also by the longitudinally extending girders 10, 11 and 12, together with the arched construction of the bottom 15 slabs. As the several girders extend from fore to aft I am able to secure a great supporting strength from each girder. The transverse strength is taken care of in a similar manner, first, by employing the main 20 girders 14', secondly, the intermediate girders and beams 19, and, thirdly, by the deck structure shown, which not only reinforces the ship transversely but also ties it together longitudinally.

25 In the construction of a sea-going vessel of reinforced concrete as above described I employ a series of outer and inner steel molds. The inner molds are first set in place and, as they conform to the interior 30 shape of the ship, it can readily be seen that the reinforcing steel may be placed in position and shaped in accordance therewith. The outer molds are then placed in position and the concrete may finally be poured. The 35 construction of the molds, together with the manner of assembling and detaining the same after the reinforcing steel has been placed in position and while the concrete is being poured, forms the subject-matter of a 40 co-pending application and will therefore not be further described. The mixture of the concrete employed may also be varied as this does not form any part of the present invention.

45 The essence of the invention resides entirely in the construction of a cellular floating vessel formed of reinforced concrete and so reinforced by girders and beams that weight and strains may be equally distributed, whether caused by external or internal causes; and furthermore a structure which combines lightness and strength in greater proportion than has heretofore been obtainable.

50 Having thus described my invention what

I claim and desire to secure by Letters Patent is—

1. In a concrete ship, a hull having a double bottom and sides which latter are double at their lower portions, a lower deck 60 having its opposite sides extending across the space between the double portions of the sides at the respective upper edges of said double portions of the sides, an upper deck, spaced vertical girders between the two decks 65 integral with each and with the parts of the hull sides between the decks, and a pair of arches extending from bow to stern, said arches being integral with the said last named hull sides, with the adjacent of said 70 vertical girders and with the lower deck and with the upper deck at the highest points of the arches, said arches extending below the lower deck and having portions integral therewith and being also integral with the 75 outer walls of said double portions of the hull sides.

2. In a concrete ship, a hull having a double bottom and sides which latter are double at their lower portions, a lower deck having its opposite sides extending across the space between the double portions of the sides at the respective upper edges of said double portions of the sides, an upper deck, spaced vertical girders between the two decks 80 integral with each and with the parts of the hull sides between the decks, a pair of arches extending from bow to stern, said arches being integral with the said last named hull sides, with the adjacent of said vertical girders and with the upper deck at the highest points of the arches, said arches extending below the lower deck and having portions integral therewith and being also integral with the outer walls of said double portions 85 of the hull sides, vertical spaced girders between the lower deck and the hull bottom, and longitudinal girders in the double portions of the hull sides, said arches also having portions integral with adjacent portions 90 of said last named vertical and longitudinal girders.

In testimony whereof I have hereunto set my hand in the presence of two subscribing witnesses.

SECONDO GILETTI.
